UNITED STATES PATENT OFFICE.

BLAN BALLARD HAYDON, OF NEW CASTLE, KENTUCKY.

CAR-COUPING.

SPECIFICATION forming part of Letters Patent No. 530,843, dated December 11, 1894.

Application filed July 10, 1894. Serial No. 517,091. (No model.)

To all whom it may concern:

Be it known that I, BLAN BALLARD HAYDON, residing at New Castle, in the county of Henry and State of Kentucky, have invented 5 a new and Improved Car-Coupling, of which the following is a specification.

My invention has for its object to provide an automatic car coupler of a simple construction, which can be uncoupled from either the 10 top or side of the car, and which will be positive in its operation.

My invention consists in such novel features of construction and peculiar combination of parts hereinafter first described in detail and 15 then specifically pointed out in the appended claims, reference being had to the accompanying drawings, in which—

Figure 1 is a perspective view of a portion of a car body with my improved coupler applied. 20 Fig. 2 is a longitudinal section of the two draw heads coupled. Fig. 3 is a horizontal section of one of the draw-heads. Fig. 4 is a perspective view of the pivoted coupling jaw detached. Fig. 5 is a detail view of the 25 coupling lever. Fig. 6 is a perspective view of the coupling link. Fig. 7 is a transverse section on the line 7—7 Fig. 2. Fig. 8 illustrates a modified form of coupling link more especially adapted for use for coupling draw- 30 heads of different heights.

In its practical construction the draw bar A is supported on the car frame in the usual manner, and has its head A' formed with a mouth having beveled side and bottom edges 35 as shown.

Referring now more particularly to Fig. 2, it will be noticed, the link mortise or chamber B, has a depression B' in the bottom which terminates at the vertical shoulder c of the 40 lower front end C of the head, which shoulder forms a link lock member, as hereinafter specified. Within the recess or depression B is held a yielding supplemental bottom member, which is in the nature of a horizontally 45 pivoted jaw D, pivoted at its rear end on a bolt d, the front end of which is normally held flush with the upper face c' of the end C, by means of a spring or cushion member E, held under such end.

50 F indicates the upper clamping jaw which is held horizontally with its front end f projected over the end C, and such end f, has a

lock shoulder f' held in line with the shoulder e of the member C. The rear end of the jaw F is pivoted on the bolt f'', while its front end 55 is normally forced downward by a spring G held under the top of the draw-head and against the jaw F as shown such spring G being stronger than the spring under the lower jaw whereby its tension will overcome the ten- 60 sion of such lower spring when the coupling link is held between the jaws for a purpose presently explained.

H indicates the coupling link, the construction of which is most clearly shown in Fig. 6 65 of the drawings, by reference to which it will be noticed, the same comprises two sections h^x formed with hinge eyes h, on their upper rear ends, which are joined by the hinge bolt h', whereby a hinged connection which allows 70 the sections h^x to swing upward, is provided. The front end of each section h^x has a coupling barb having opposite coupling shoulders h³.

So far as described it will be readily seen 75 that normally the sections h^x of the link will be held horizontally thereby holding the outer end always in position for coupling.

Now assuming that the draw head having the link member is approaching the opposite 80 draw-head, the front section h^x as it engages the face of the opposite draw-head will rise and travel up the beveled face of the end C and be forced in between the jaws D and F, and as its shoulders h³ pass the shoulders f' 85 and c the upper jaw, owing to the increased pressure of its spring will force the lower shoulder on the end h³ down back of the shoulder c while the upper shoulder will engage the shoulder f'.

J indicates a vertically disposed rock shaft journaled in the draw-head at one side, it passing through slots d^x f^x in the clamp members D and F, and such shaft J has a crank or bail portion J' which is fitted to project between the members D and F as most clearly shown in Fig. 7. At the point where the bail projects the said member F has a rearwardly beveled portion F' inclined and so arranged that when the shaft is turned parallel with the 90 side wall of the draw-head, the clamp members will be held free to move to their coupled positions. When however such shaft J is turned at right angles as shown in Fig. 7 the 100

jaw F will be spread apart from the lower jaw, which, owing to its yielding condition will immediately move the barb end of the link flush with the member C and place it in position 5 for withdrawal. The link members have slots in their ends so that they can be readily coupled with the ordinary link and pin couplings.

In practice the shaft J is connected with 10 operating mechanism extended to the top and sides of the car whereby it can be set to the uncoupling position from either the side or the top.

In Fig. 8 I have illustrated a modified form 15 of link, in which the hinged coupling members are capable of being swung up in reverse directions and are forced to their downward or normal pressure by a flat spring held secured on the central or body portion by a staple member as shown, such construction adapting the link to readily couple with draw- 20 heads of different heights.

Having thus described my invention, what 25 I claim, and desire to secure by Letters Patent, is—

1. The combination with the draw-head having a transverse coupling shoulder at the front end of the bottom of the mortise, and a yielding member held in such bottom with its front 30 end normally flush with top of the said front end of the said mortise bottom, of a coupling jaw held in the top of the mortise pivoted at its rear end, and having its front end spring pressed toward the bottom of the mortise, its 35 front end having a transverse coupling flange on its under face, the link having its ends

beveled and formed with transverse coupling shoulders, and means for uncoupling, all arranged substantially as shown and for the purposes described. 40

2. In a car coupling the combination with the draw-head A having a coupling shoulder c and a recess C in the bottom, and a yielding member D in the said recess, of the pivoted coupling jaw F having a coupling flange 45 f disposed above the shoulder c, a spring for forcing the front end of such jaw downward, said spring having a pressure greater than the yielding pressure of the member D, the link H provided with transverse coupling 50 shoulders and means for uncoupling all arranged substantially as shown and described.

3. The combination, with the draw-head A provided with a yielding member in the bottom of its mortise, and a coupling shoulder c 55 at the front end of such bottom, and the coupling jaw F pivoted at its rear end in the mortise, a spring for forcing the front end downward said end having a coupling flange f said jaw having an inclined recessed portion at 60 one side, of the uncoupling shaft J, journaled vertically in the draw-head having a winged portion adapted to be swung into engagement with the said inclined recess of the jaw F, and thereby force it upward against its spring 65 tension and means for operating the shaft from the top or sides of the car all arranged substantially as shown and described.

BLAN BALLARD HAYDON.
